(57) CLAIM

The ornamental design for a confection box, as shown and described.

DESCRIPTION

FIG. 1 is a perspective view of a confection box showing my new design;

FIG. 2 is a top plan view thereof;

FIG. 3 is a bottom plan view thereof;

FIG. 4 is a side elevation view thereof; and,

FIG. 5 is a perspective view of the bottom of the confection box partially opened showing the manner in which the box bottom is folded to form its ultimate shape.

1 Claim, 5 Drawing Sheets
